G. NETH.
WIRE STRETCHER FOR PACKING BOXES.
APPLICATION FILED SEPT. 24, 1919.

Patented Nov. 8, 1921.

By his Attorney
Inventor
George Neth
John Lotka

UNITED STATES PATENT OFFICE.

GEORGE NETH, OF NEW YORK, N. Y.

WIRE-STRETCHER FOR PACKING-BOXES.

1,396,229.

Specification of Letters Patent.

Patented Nov. 8, 1921.

Application filed September 24, 1919. Serial No. 325,857.

To all whom it may concern:

Be it known that I, GEORGE NETH, a citizen of Germany, and resident of the borough of Manhattan, city, county, and State of New York, have invented certain new and useful Improvements in Wire-Stretchers for Packing-Boxes, of which the following is a specification.

My invention relates to devices for stretching wires around packing-cases, boxes, and the like, such wires being used quite commonly to secure the lid or cover of the box or case more reliably than this can be done with nails alone. The object of my invention is to provide a very simple and compact device or tool of the above-indicated character, which will be readily manipulated and which has its moving parts well protected so as to guard against injury to the device and to the workman as well.

A satisfactory and preferred embodiment of my invention will now be described in detail in connection with the accompanying drawings, and the novel features will then be pointed out in the appended claims.

In the said drawings Figure 1 is a side elevation of the improved wire-stretcher in use on a box or case; Fig. 2 is a corresponding longitudinal central section; Fig. 3 is a corresponding plan view; Figs. 4 and 5 are vertical cross sections on lines 4-4 of Fig. 1 and 5-5 of Fig. 3 respectively; and Fig. 6 is a cross section on line 6-6 of Fig. 3, with parts omitted.

The improved wire-stretcher comprises a bar A provided at its forward or fulcrum end with a narrow tongue A' at the sides of which are parallel vertical flanges A'' extending upwardly and forming between them a longitudinal channel for the reception of one end of the wire B. The bottom of this guide channel is above the top surface of the bar A, so that said end of the wire does not come in contact with such top surface. The wire B passes around the bale, box, or case C in the usual way, and is bent or twisted at its other end into a loop B', adapted to be placed around the tongue A' and its flanges A'' as shown in Figs. 1, 2, 3, 4 and 6, the wide portion of the bar A forming

a stop for said loop, and the opposite, substantially straight end of the wire being passed through said loop. At its forward end, at each side of the tongue A', the bar A is provided with two longitudinal projections A* 55 of greater length than said tongue, and adapted by their engagement with the case C or the like, to form a fulcrum about which the bar is swung, said projections at the same time serving to hold the tongue A' 60 away from the box or case, so that the wire lying in the channel of the tongue A' may not be forced into the material of the case and thus injured. The straight end of the wire B is held fast in any suitable manner, 65 say by a clamp of the kind shown in Figs. 3 and 5, which comprises a slide D embracing the bar A so as to be adapted to travel lengthwise thereof, but held against turning. This slide carries a fixed jaw E, preferably 70 toothed, and a movable jaw E' pivoted at F and provided with a clamping surface or cam surface adjacent to the fixed jaw, said cam surface being preferably toothed. The straight end of the wire B may be laid between the two jaws from above, or threaded 75 between them endwise, if preferred, and by swinging the handle E'' of the movable jaw, the latter will be made to clamp this end of the wire. The cam surface is so arranged 80 that the wire will be gripped more tightly when it is pulled or stretched by the movement of the slide D, produced by mechanism to be described presently.

With the slide D is connected rigidly a rod 85 G, as by screwing the threaded end of said rod tightly into the slide. This rod extends longitudinally of the bar A, that is to say, in the direction of the path in which the slide travels, and is secured at its other end to a 90 slide G' straddling the bar A at a distance from the slide D, to move lengthwise of said bar. The slide G' is made with an internally-threaded sleeve G'' the axis of which is longitudinal with respect to the bar A. 95 This sleeve G'' is in engagement with the external screw-thread H' of a rotary rod H journaled in or upon brackets J which are secured to the bar A rigidly. On the bar portion carrying the brackets J is also se- 100

cured another bracket K to which is secured rigidly a short transverse axle L the axis of which intersects that of the sleeve G'' and of the rod H. On this axle L is mounted to 5 turn a bevel wheel M which, on its side nearest the tongue A', is in mesh with a bevel wheel or pinion N secured rigidly to the rod H adjacent to the forward bracket J, but on the rear side thereof. It will be understood 10 that the bevel wheel M assists in preventing rearward movement of the rod H, the brackets J holding said rod against longitudinal movement in either direction. Preferably, as shown, the wheel M is considerably larger 15 than the pinion N. The wheel M carries two studs or screws M' projecting outwardly, in a direction parallel to the axis of said wheel, and preferably at equal distances from said axis. To turn the wheels M, N 20 and rod H, I provide the detachable crank O having two eccentric openings adapted to receive the studs M'.

The rear end of the bar A is provided with a steady portion P which may be in the 25 nature of a hand grip, or any other suitable device for holding the bar relatively steady with one hand while the workman turns the handle of the crank O with the other hand.

The manner of using this improved wire-stretcher will be understood readily. The 30 stretcher having been hung on the flanges A'' loop B' having been hung on the flanges A'' of the tongue A', and the body of the wire having been passed around the bale, box, case, or other article, the substantially 35 straight free end of such wire is passed through the loop B' and between the jaws E, E', the projections A* at the forward end of 40 E'' is swung to grip this end of the wire, and the bar A resting against the case C at or near a corner thereof. The clamp handle 45 E'' is swung to grip this end of the wire, and by turning the crank O the workman will rotate the rod H and thus pull the slide G', rod G, and clamp D with the straight wire end toward the rear of the tool, that is to say, toward the hand grip P, thus stretching 50 the wire. When the proper amount of stretch has been secured, the tool is swung about the fulcrum formed by the case C engaging the projections A*, thereby forming 55 a sharp bend or kink where the clamped end of the wire passes through the loop B', whereupon the clamp handle E'' can be swung to release the wire without having to fear that the wire tension may become relaxed materially, since the bent end of the wire will have a good hold on the loop B'. The tool may then be removed from the box or case, the previously clamped end of the wire being secured firmly in the usual way, 60 by bringing said end back against the body of the wire and twisting it around said body with pliers.

In order to protect the thread of the rod H, I provide a cover plate Q connecting the

two brackets J and extending above the said 65 rod and the sleeve G'', partly with a view of protecting these parts against dust and other foreign matter which might clog them, and partly as a safeguard against the operator's getting his fingers caught in the moving 70 parts. Said cover Q is also in guiding engagement with an upward extension G* rigid with the slide G'. This extension has a hole (Figs. 1 and 2) in a position corresponding to that of the hole through which 75 passes the bolt for connecting the rod G with the slide G'. Thus, if the lower portion of the slide should break, such slide can be turned around 180°, after loosening the rod G, to bring the extension G* into guiding 80 engagement with the bar A, the rod G being then secured to the extension G*. Normally, with the slide G' engaging the bar A, and the extension G* engaging the cover Q, the slide is guided very firmly.

The flanges A'' raise the looped end of the wire B off the box or case C and as the tool is swung on its end, the wire remains as tight as it has been made by the turning of the handle O, that is to say, there is no slackening or sagging of the wire during this swinging of the tool, and there is no necessity for turning the handle O to tighten the wire beyond the desired point, to allow for expected slackening or sagging; such overstretching 90 of the wire of course exposes it to strain and breakage.

Various modifications may be made without departing from the nature of my invention as set forth in the appended claims.

I claim:

1. A wire-stretcher comprising a bar, a wire-holding slide movable along one portion of said bar, a threaded member mounted to turn adjacent to another portion of the 105 bar but held against longitudinal movement, a second slide guided along such other portion of the bar and having threaded engagement with said rotary member, a longitudinal rod connecting the two slides, and 110 means for operating said rotary member.

2. A wire-stretcher comprising a bar provided at one end with a wire-guiding projection and with two projections of greater length than the wire-guiding projection, located at each side thereof, a wire-holder movable lengthwise of said bar, and means 115 for operating said holder.

3. A wire-stretcher comprising a bar provided with a relatively short wire-guiding 120 projection at one end and with a relatively long projection at the side of said first-named projection, a wire-holder movable lengthwise of said bar, and means for operating said holder.

4. A wire-stretcher comprising a bar provided at one end with a projection having a longitudinal wire-guiding channel the bot-

tom of which is above the top surface of said bar, a wire-holder movable lengthwise of said bar, and means for operating said holder.

- 5 5. A wire-stretcher comprising a bar, brackets secured thereto, a rotary member journaled in said brackets, a slide having threaded engagement with said member and movable lengthwise of said bar, a cover ex-

tending over said member and slide and in 10 guiding engagement with said slide, a wire-holder likewise movable along said bar and connected with said slide, and means for operating the slide and the wire holder.

In testimony whereof I have signed this 15 specification.

GEORGE NETH.
